UNITED STATES PATENT OFFICE.

BASYL FEDORKO, OF ANSONIA, CONNECTICUT.

ENVELOP-OPENER.

1,400,946.

Specification of Letters Patent. Patented Dec. 20, 1921.

Application filed February 24, 1921. Serial No. 447,477.

To all whom it may concern:

Be it known that I, BASYL FEDORKO, a citizen of Ukraine, residing at Ansonia, in the county of New Haven and State of Connecticut, have invented certain new and useful Improvements in Envelop-Openers, of which the following is a specification.

This invention relates to attachments for envelopes for the purpose of expediting the opening of the same, and has for one of its objects to improve the construction and increase the efficiency and utility of devices of this character.

Another object of the invention is to provide a simply constructed device which may be readily applied without material change of envelopes of various sizes and forms, and which may be readily transferred from one envelop to another, or from an envelop which has been opened to an unused envelop, so that the device may be repeatedly used.

Another object of the invention is to provide a simply constructed device whereby an envelop may be quickly opened without injuring the contents of the same.

With the above general objects in view and others that will become apparent as the nature of the invention is better understood, the same consists in the novel form, combination and arrangement of parts hereinafter more fully described in connection with the accompanying drawing and in which like reference characters designate corresponding parts throughout the several views.

35 In the drawing,

Figure 1 is an elevational view of an envelop sealed or closed with the improvement constituting the present invention, applied,

Fig. 2 is a top view thereof,

40 Fig. 3 is a fragmentary elevational view of an envelop and the device of the present invention as it appears when the envelop is being opened, and

Fig. 4 is a perspective view of the envelop 45 opener.

The present envelop opener may be applied to envelopes of various sizes and forms and without mutilating the envelop, but for the purpose of illustration, it is shown 50 applied to a conventional envelop involving the usual body portion composed of a front member with a back 5 and end flaps 6 and 7, as well as a closure flap 8.

The improved attachment comprises a 55 strip of flexible material, such as relatively thin sheet metal and embodies a blade 9 hav-

ing an upper sharpened edge 10 and provided with a stirrup 11 at one end which merely comprises a folded-over lug provided on said end of the blade. The blade 9 is provided 60 with a laterally projecting lug 12 adjacent its other end, and this lug as well as the adjacent end portion of the blade indicated at 13 is adapted to be bent for a purpose and in a manner which will presently be made 65 apparent, it being noted that the end 13 and lug 12 are formed of sufficient strength and the like to cause them to firmly remain in bent position.

When an envelop is to be equipped with the present device, the stirrup 11 is disposed upon the upper edge of the letter 14 which is contained within the envelop so that the blade 9 is supported adjacent the fold line between the closure flap 75 8 and the front of the envelop body. The device is then slid toward the adjacent end of the envelop so as to pierce it at the fold line between one of the flaps 6 or 7 and the front of the envelop body so that said end projects outwardly. This end is then bent 80 upon itself to engage the desired outer face of the envelop as shown in Fig. 1, the lug 12 is then directed through the envelop at the fold line of the flap 8. The lug 12 is 85 then also bent upon itself to engage the outer face of the flap 8 as is also shown in Fig. 1 and the flap 8 is then sealed. In this position, the device does not cause the envelop to appear bulky or cumbersome and the presence 90 of the opener is not perceptible from an unsightly standpoint, the only difference in the appearance of the envelop being the presence of the folded end 13 and lug 12.

It will also be noted that the letter is utilized 95 to support the blade adjacent the fold line of the flap 8, so that when the end 13 and lug 12 are unfolded to the dotted line position of Fig. 1, they may be utilized as finger pieces for upwardly tilting the device 100 so as to sever the envelop along the fold line of the flap 8 upon movement of the opener along the upper edge of the letter, and without danger of mutilating the letter. It will be observed that the upward tilting movement 105 of the opening device is readily accomplished by the fulcruming of the stirrup 11 upon the upper edge of the letter. Thus, the opening operation is quickly accomplished, and if desired, the device may 110 be retained for application to another envelop.

From the foregoing description, it is believed that the construction and operation, as well as the advantages of the present invention will be readily understood and appreciated by those skilled in the art.

Minor changes may be made without departing from the spirit and scope of the invention as hereinafter claimed.

What is claimed as new is:

- 10 1. An envelop opener comprising a metal blade having a stirrup at one end for engagement with the upper edge of a letter so as to support the blade adjacent the fold line of an envelop closure flap, the blade 15 having its other end formed to be projected through the fold line at one side of the envelop, whereby said end may be engaged for upwardly tilting and sliding the blade for severing the envelop along the fold line 20 of said closure flap.
2. An envelop opener comprising a metal blade having a stirrup at one end for engagement with the upper edge of a letter so as to support the blade adjacent the fold 25 line of an envelop closure flap, the blade having its other end formed to be projected through the fold line at one side of the envelop, whereby said end may be engaged for upwardly tilting and sliding the blade for 30 severing the envelop along the fold line of said closure flap, said projecting end of the blade being flexible so as to be bent upon the envelop, and the blade end being of such material as to insure remaining of the end 35 in folded condition as well as to permit unfolding of the same.
3. An envelop opener comprising a metal blade having a stirrup at one end for engagement with the upper edge of a letter so 40 as to support the blade adjacent the fold line of an envelop closure flap, the blade having its other end formed to be projected through the fold line at one side of the envelop, whereby said end may be engaged for 45 upwardly tilting and sliding the blade for severing the envelop along the fold line of said closure flap, said projecting end of the blade being flexible so as to be bent upon the envelop, and the blade end being of such material as to insure remaining of the end 50 in folded condition as well as to permit unfolding of the same, said blade being provided with a laterally projecting lug adjacent its projecting end adapted to be forced 55 through the envelop at the fold line of the closure flap of the same, and said lug be-

ing also bendable or foldable against the outer face of the closure flap as well as unfoldable for being grasped together with the projecting end of the blade when desiring 60 to open the envelop.

4. An envelop opener including a blade having a sharpened edge and provided with a stirrup at one end for reception of the upper edge of a letter whereby the blade is 65 supported substantially parallel with the upper edge of the letter and within the fold of the closure flap of the envelop, and a member upon the opposite end of the blade accessible from the exterior of the envelop 70 for manipulating the blade to sever the envelop along said fold line of the closure flap.

5. An envelop opener including a blade having a sharpened edge and provided with 75 a stirrup at one end for reception of the upper edge of a letter whereby the blade is supported substantially parallel with the upper edge of the letter and within the fold of the closure flap of the envelop, and a 80 member upon the opposite end of the blade accessible from the exterior of the envelop for manipulating the blade to sever the envelop along said fold line of the closure flap, said accessible member including a laterally 85 projecting lug carried by the blade and arranged to be forced through the envelop at the closure flap fold line.

6. An envelop opener including a blade having a sharpened edge and provided with 90 a stirrup at one end for reception of the upper edge of a letter whereby the blade is supported substantially parallel with the upper edge of the letter and within the fold of the closure flap of the envelop, and a 95 member upon the opposite end of the blade accessible from the exterior of the envelop for manipulating the blade to sever the envelop along said fold line of the closure flap, said accessible member including a lat- 100 erally projecting lug carried by the blade and arranged to be forced through the envelop at the closure flap fold line and said lug being bendable upon itself to engage the outer face of the closure flap.

In testimony whereof I affix my signature in presence of two witnesses.

BASYL FEDORKO.
